TAPE RECORDER CABINET

Chester J. Barecki, Grand Rapids, Mich., assignor to American Seating Company, Grand Rapids, Mich., a corporation of Delaware

Filed Mar. 26, 1968, Ser. No. 11,143

Term of patent 14 years

Int. Cl. D6—01

U.S. Cl. D33—19

FIG. 1

The top of the cabinet is plain and conventionally flat.

I claim:

The ornamental design for a tape recorder cabinet, as shown and described.
